TEST PICK

Paul Griffith Edwards, Millburn, and Charles Edward Clutts, Clifton, N. J., assignors to American Telephone and Telegraph Company, a corporation of New York

Application May 4, 1933, Serial No. 689,438

4 Claims. (Cl. 200—16)

This invention relates to electrical apparatus such as keys, switches, test picks and the like.

One form of test pick quite generally used for making temporary electrical connections to various conductors forming different circuits or different pieces of apparatus, consists of a pointed metallic rod having a handle made of wood, bakelite or other insulating material which partly surrounds the metallic rod, the unpointed end of the metallic rod having a terminal for a conductor which may be connected to testing or other apparatus. But this type of device, when applied to each of the conductors of a plurality of circuits or to their terminals, does not afford means for quickly switching connections from one circuit to another circuit, both of which are used for testing purposes, unless a key or switch, or the like, is employed in addition to the pick. To overcome these limitations this invention has been evolved and it consists of a novel form of test pick which may be viewed in general as a unitary structure combining the features of the old fashioned test pick and a key or switch, or the like.

This invention will be better understood from the detailed description hereinafter following when read in connection with the accompanying drawing, in which Figures 1 and 2 show two embodiments of the invention given merely for the purpose of illustration.

Referring to Fig. 1 of the drawing, the reference character 1 designates a shell or handle which is made of an insulating material such as fibre, bakelite, etc., and it is preferably cylindrical in shape. The shell 1 surrounds two sleeves 2 and 2', both of which are metallic and therefore electrically conductive. The sleeves 2 and 2' are also cylindrical in shape, and insulated from each other by a fixed member or insulator formed by the shoulder 12 of the insulator 3.

The pick 4 is a pointed rod-like metallic element such as brass, and it slides within two bearing surfaces, one of which is formed by the center aperture of the insulator 3, and the other by a similar aperture in a concentric terminal bushing 11 which is also made of an insulating material. A coil spring 8 is inserted between the fixed insulator 3 and the collar 9 which is mounted on and permanently fastened to the pick 4 by means of a set-screw, as shown. The coil spring 8 serves normally to maintain the pointed end of the pick as far to the right as possible.

A collar 5 is also mounted on and permanently fastened to another section of the pick 4 by means of a set-screw, as shown. Still another

collar 6 is permanently fastened to the sleeve 2' by means of a set-screw, and it will be evident that the collar 6 is normally insulated from the pick 4 by the air space therebetween. The collars 5 and 6 serve both as metallic contacts and as stops for limiting the movement of the pick 4 in one direction, i. e., to the right. A plug 12 is inserted at the base of the shell 1, i. e., at its left, and within the center of the plug 12 is inserted a metallic screw designated 7 which may be equipped at the end distant from its head with a contact point A. The unpointed or left-hand end of the pick 4 is also equipped with a centrally located contact point B which is directly in line with the contact A. The left-hand end of the sleeve 2' may carry a lug or terminal such as 10 which is employed for making one of the electrical connections to the testing or other apparatus (not shown). The head of the screw 7 may be employed for making another electrical connection to the latter apparatus or to other testing apparatus. It will be noted that the contact point A limits the movement of the rod or pick 4 in the opposite direction, i. e., to the left, and in its extreme position the contacts A and B are conductively connected to each other.

The conductor extending to the lug 10 may be considered as part of one of two circuits incorporated in the testing apparatus above mentioned and this circuit may be termed, for convenience of description, the first circuit. The conductor extending to the head of the screw 7 may be considered as part of the other of the two circuits of the testing apparatus and this may be termed the second circuit.

If it is desired to connect the first circuit of the testing apparatus to a circuit to be investigated or to one of its conductors or terminals, and then to transfer the circuit to be investigated to the second circuit of the testing apparatus, it will be necessary to bring the pointed or right-hand end of the pick 4 against and in contact with the circuit to be investigated. This will establish a conductive path from the lug 10 along the sleeve 2' through collars 6 and 5 to the tip 45 of the pick 4. Inasmuch as the conductor extending to the lug 10 is part of the first testing circuit, then the latter conductive path, just described, will establish an electrical connection between the first testing circuit and the circuit to be investigated.

Just as soon as it is desired to transfer the connection of the circuit to be investigated from the first testing circuit to the second testing circuit which extends to the conductor terminating 55

at the head of the screw 7, then the handle or shell 1 of the arrangement will be pressed or pushed forward, i. e., to the right, so that the pointed end of the pick 4 will be in contact with one of the conductors of the circuit to be investigated under pressure. The pick 4 will be moved to the left with respect to the handle or shell 1 and in its extreme position at the left the contacts A and B will be closed. Immediately after 10 the collar 5 breaks its contact with the collar 6, the first testing circuit will be dissociated from the circuit to be investigated. And upon the subsequent closure of contacts A and B, the circuit to be investigated will be connected to the second testing circuit, the intermediate conductive path comprising the pick 4, contacts B and A, the screw 7 and the conductor connected to the head of screw 7. When the pressure applied to the handle 1 becomes released, the pick 4 will be moved 15 to the right with respect to the handle or shell 1, so as to break the circuit between the contacts A and B. The spring 8 will return the pick to its normal position, which is as far to the right as collar 5 will allow it to go, the extent of 20 the motion of collar 5 to the right being determined by the location of the collar 6.

The time required for transferring the connection of the circuit to be investigated from the first testing circuit extending to the lug 16 to 30 the second testing circuit which extends to the head of the screw 7, is dependent upon a number of factors such as the spacing and relative locations of the collars 5 and 6, the maximum distance between contacts A and B, which may be 35 varied by changing the length of the pick 4, the speed with which the handle 1 is depressed, the size and relative proportions of the spring 8, and so on.

Fig. 2 shows another type of test pick. This 40 arrangement includes a cylindrical shell or handle 21 which may be of insulating material, one end of which, i. e., at the right, is internally threaded. A bushing 22, also of insulating material, has a threaded shoulder which engages the internal screw threads at the right-hand end 45 of the shell 21. Bushing 22 has a central aperture which is concentric with respect to the central aperture of a collar 23 which is immovable, collar 23 being permanently fastened to 50 the shell 21 by means of a set-screw 24.

The pick 25 is slidably located within the central apertures of the collar 23 and the bushing 22. The unpointed end of the pick 25 has a screw-threaded external surface which engages 55 the member 26, the member 26 being cup-shaped and internally threaded within the cupped portion so as to engage the external screw threads at the unpointed end of the pick 25. The member 26 is made of a conductive substance such as brass or the like and it is conical or otherwise pointed in shape at its left-hand end.

A collar 27 is mounted upon the pick 25 within the shell or handle 21, this collar being permanently fastened to some point along the outer 65 surface of the pick 25. A set-screw may be used for fastening the collar 27 to the pick 25, as shown. Another collar 28 is permanently fastened to the shell 21 by means of a set-screw as shown and this collar has a wide, central aperture which may be circular in shape. A helical spring is positioned about the pick 25 and within the central aperture of the collar 28, this spring being located between collars 23 and 27. This 70 spring produces a continuously acting pressure 75 against the left-hand side of the movable collar

27 and therefore the pick 25 will normally be positioned as far to the right as possible when considered with respect to the shell 21. The spring may be compressed sufficiently by the application of pressure to the shell 21 so as to allow the left-hand side of the collar 27 to contact at its edge one side of the collar 28 and when this happens, the pick will be located as far to the left as possible.

The shell or handle 21 also surrounds a jack 10 arrangement which includes three springs designated 30, 31 and 32, the springs 30 and 32 being relatively fixed and immovable while the spring 31 may be moved laterally at its right-hand end so as to contact either of the springs 30 or 32. 15 At their left-hand ends the springs 30, 31 and 32 are spaced from each other by insulators 33. The insulators 33 and the springs 30, 31 and 32 are fastened together within blocks of insulation 34 by means of a pair of screws 35 which may be 20 placed within a corresponding pair of bushings 36 which are made of insulating material, the screws 35 being threaded so as to engage the base of the insulating member 34, as shown. Three metallic lugs 36, 37 and 38 are conductively 25 connected to the springs 30, 31 and 32 and each of these may be connected to a wire or conductor. The insulating member 34 is fixed in position within the shell 21 by means of a number of set-screws which are designated 40. 30

The right-hand end of the spring 31 is spoon-shaped so as to be slidable along the pointed outer surface of the metallic member 36. The spoon-shaped end of the spring 31 is always in contact with the member 36 although its location about 35 the outer surface of this member may be changed depending upon whether or not pressure is applied to the shell 21. When no pressure is applied to the shell 21, the pick 25 will be located as far to the right as possible with respect to the shell 21 40 and the springs 31 and 32 will be conductively connected to each other. When the springs 31 and 32 are conductively connected to each other, a conductive path will be provided along the pick 25, through the cup-shaped member 26 and along 45 the parallel path established by the springs 31 and 32 which terminate in the lugs 37 and 38, respectively.

When pressure is applied to the shell 21, the spring 28 will be compressed and the pick 25 will 50 be moved to the left with respect to the shell 21 until the collars 27 and 28 meet each other. At the same time, the spoon-shaped end of the spring 31 will be lifted upon the steeply graded outer surface of the cup-shaped member 26, thereby 55 first breaking the contact between springs 31 and 32 and subsequently making contact between the springs 31 and 38. When this occurs, the conductive path will include the pick 25, the cup-shaped member 26, the parallel paths established 60 by springs 30 and 31 and the lugs 36 and 37 which are conductively connected to these springs, respectively.

When the pressure applied to the shell 21 is 65 subsequently released, the spring 28 will cause 70 the pick 25 to move to the right as before, the motion to the right being terminated when the right-hand side of the member 26 meets the left-hand side of the collar 28. This will cause the circuit between the springs 30 and 31 to be opened 75 and the spring 38 will no longer be conductively connected to the pick 25. When the pick 25 has reached its extreme position at the right, springs 31 and 32 will again be conductively connected to each other. 75

While this invention has been shown and described in certain particular arrangements merely for the purpose of illustration, it will be understood that the general principles of this invention 5 may be applied to other and widely varied organizations without departing from the spirit of the invention and the scope of the appended claims.

What is claimed is:

1. A test pick comprising a handle of insulating material which is cylindrical in shape and lined with a metallic member having a hollow center, a metallic rod pointed at one end and concentric with the handle, means including a spring for retaining the unpointed end of said rod in a pre-determined position within the hollow section of said handle, a fixed electrical terminal insulated from the lining of said handle, the handle being depressible in the direction of the pointed end of said rod so as to change the relative position of said rod with respect to said handle by a pre-determined distance and to contact said fixed electrical terminal, and mutually independent electrical circuits completed from the rod to the metallic lining of said handle or to said fixed electrical terminal when it reaches its two extreme positions, said metallic rod being alone common to said mutually independent electrical circuits.
2. A testing device comprising a metallic rod pointed at one end, an insulated holder having a hollow center and a metallic lining, the unpointed end of said rod being slidably mounted within the center of said holder, means for normally maintaining the pointed end of said rod a predetermined distance away from said holder and in electrical contact with the lining of said holder, a fixed terminal normally spaced from the unpointed end of said rod, and means responsive to the application of pressure to the holder to reduce the distance between the pointed end of said rod and said holder by a predetermined amount

so that said rod will make electrical contact with said fixed terminal.

3. A manually operated unitary test pick comprising a handle of dielectric material having a hollow central section, a metal pick, means for sliding said pick through the central section of said handle, a first conductive element limiting the movement of said pick into the central section of said handle, means including a second conductive element limiting the movement of 10 said pick out of the hollow central section of said handle, and means for normally retaining said pick in contact with said second conductive element.

4. A test pick comprising a hollow cylindrical 15 shell of insulating material, two metallic linings for said shell, both of the same internal diameter, a stationary insulator located within said shell and spacing one of said linings above the other, a plug of insulating material located at the lower 20 end of said shell, a long metallic rod pointed at one end, said insulator and said plug having concentric apertures through which said rod may slide, a plug of insulating material having a central aperture located at the upper end of said 25 shell, a conductive element passing through the aperture of the latter plug so that the unpointed end of said rod may contact therewith, a collar permanently fastened to said rod, said collar being positioned between the plug at the lower 30 end of the shell and said insulator, a coil spring interposed between said collar and said insulator and around said rod, and two concentric metallic collars, one of which is permanently fastened to said rod above said insulator and the other fastened to the upper lining so that they may electrically contact each other and limit the movement of said rod.
